HERNIA TRUSS

Thomas J. Le Cras, Toronto, Ontario, Canada

Application January 10, 1934, Serial No. 706,056

4 Claims. (Cl. 128—100)

The principal objects of this invention are to provide a truss which will eliminate many of the discomforts experienced by persons afflicted with hernia, and which will closely simulate the effect produced by the repression of the hernia with the person's own fingers.

A further and important object is to provide a truss, the pad of which may be very readily adjusted upon the belt to increase the comfort of the patient.

The principal feature of the invention consists first, in the novel provision of a secondary pad movably mounted upon the main pad in such a manner that an inwardly and upwardly thrusting pressure is applied in the locus of the hernia through the connection of the perineal strap to the pad.

A further feature of importance consists in the novel construction of the main pad in simulation of the fingers of the hand, and a further feature of the invention consists in the novel construction and arrangement of the clip for securing the main pad to the belt whereby the angularity of the pad may be readily adjusted in relation to the belt.

In the accompanying drawing, Figure 1 is a perspective view of a hernia belt furnished with my improved finger action pad.

Figure 2 is an enlarged plan view of the outer side or back of the pad.

Figure 3 is a plan view of the inner side or face of the pad.

Figure 4 is an enlarged longitudinal section through the pad and belt showing the position of the inner or supplementary pad in position to be applied to the body.

Figure 5 is a sectional view similar to Figure 4 showing the perineal strap attached to the lever for operating the inner pad and the inner pad in its raised position.

Throughout a period of many years a very extensive number of trusses have been invented and marketed for the alleviation of the discomforts of hernia, but the devices so far provided have left much to be desired.

It is understood and appreciated by those afflicted with hernia and those whose special province it has been to minister to their comfort, that hernia can be most effectively relieved by the application of the patient's own fingers placed over the afflicted area. In the use of the fingers the patient involuntarily or voluntarily presses upwardly and inwardly to relieve the stress and this present invention endeavours to accomplish a close simulation of this action.

The pad 1 is preferably formed of a substantially oval shape having the bottom end thereof partially divided to represent the size and shape of three of the fingers of a person's hand, the central finger 2 being longer than the fingers 3 and 4. This pad is preferably moulded of rubber or a rubber composition and is curved longitudinally in an arc shape.

Across the back or outer side of the pad 1 there is formed an angularly arranged transverse depression 5 which forms a groove to receive the belt 6.

A rivet or bolt 7 is secured in suitable metal fastenings 8 in the body of the pad intermediate of the width of the depression 5 and upon the head of this bolt is mounted a clip for securing the belt in position, which in the form shown in Figure 1, is constructed of a length of wire bent to form a plurality of looped hooks between which the belt is inserted and from between which the belt can be easily removed.

In the form shown in Figure 2 the clip 10 is formed of sheet metal having a plurality of hook members 11 adapted to fit over the edges of the belt.

A slot 12 is arranged longitudinally of the central finger 2 of the pad 1 below the transverse depression 5 and in this slot is embedded a plate 13 which may be of metal or suitable hard material such as bakelite, and this plate 30 is provided with a narrow longitudinal slot 14.

A pivot pin 15 extends through the side walls of the plate 13 and across the slot 14, and on this pin is pivotally mounted a lever 16 which is formed with a hook 17 at one end which extends through the back of the slot 12 of the pad 1 and pivotally supports the inner or secondary pad 18. This inner pad is of oval formation in plan and is convexed on its inward side, its outer side being recessed to receive a plate 19 and preferably being convexed to conform to the concaved inner surface of the main pad on which it is shiftable. The pad 18 is thus received within the hollow of the main pad and the edge portions of the main pad 1 are adapted 45 for snug pressure contact with the body of the wearer. This plate is slotted longitudinally and has a cross bar 20 which forms the pivot support for the pad and rests in the hook 17.

The outer end of the lever 16 is provided with 50 a hook 21 which is adapted to receive the metal loop 22 secured on the free end of the perineal strap 23 which is adjustably mounted on the belt 6.

It will be readily understood that when the 55

loop 22 of the perineal strap is placed in the hook 21 of the lever 16 the pull of the strap will pull downwardly upon the lever, thereby moving the inward end thereof upwardly and as the 5 inner end supports the inner pad 18, said inner pad will be forced in an upward direction with a wedge-like action between the main pad and body of the wearer, and this upward movement is first effected by an inward pressure against 10 the body through the swinging action of the lever. This inward pressure and upward movement of the inner pad has the effect of pressing inwardly and then wedging upwardly against the hernia area in a manner very closely simulating the 15 action of the human fingers, and the use of this pad will for this particular reason be of very material benefit and comfort to the wearer.

The main pad being made of a semi-flexible rubber material, also presses against the body 20 in such a way as to fit snugly in any desired fixed position, and the finger ends simulate the human finger ends. These finger ends are reinforced by the lateral portions 24 of the metal loop 22 carried by the perineal strap. These 25 lateral looped members apply a constant pressure against the outer fingers to hold them snugly in position.

It will be readily seen that the oval concaved 30 shape pad 1 may be adjusted on its pivotal support in relation to the belt so that the slant of the fingers may be made to accommodate the particular person on whom the belt is used.

The belt is placed in position with the inner 35 pad arranged at a suitable point low down on the hernia area, and upon the connecting of the perineal strap and the straightening of the body of the wearer, the inner pad is pressed inwardly and upwardly and relieves the stress otherwise predominant at that point.

40 The device is extremely simple, but very effective in use.

What I claim as my invention is:—

1. In a hernia truss, a belt, a pad carried by 45 said belt for snug engagement with the affected area and having a longitudinal slot therethrough, a lever extending through said slot and pivotally mounted intermediate of its length and having

hooked ends, a secondary pad having a recess, a pin extending across said recess and engaged by the inner hook end of said lever, a perineal strap, and a loop on said strap adapted to engage the outer hook end of said lever and also to engage the back of said pad.

5

2. In a hernia truss, a belt, a pad carried by said belt for snug engagement with the affected area, a lever pivoted on said pad to swing in a plane intersecting the inner surface of said 10 pad and extending on the inner side thereof, a secondary pad mounted on said lever and bodily movable upwardly thereby, independently of the first-mentioned pad when said lever is swung on its pivot, and a perineal strap connected with 15 said lever at a point spaced from its pivotal connection with the first-mentioned pad to swing said lever and thereby bodily displace the said secondary pad.

3. In a hernia truss, a belt, a pad carried by 20 said belt for snug engagement with the affected area, a lever extending transversely through said pad and pivoted thereon, a pad pivotally mounted on the inner end of said lever and bodily displaceable therewith over the inner side of the 25 first-mentioned pad, and a perineal strap having an operating connection with the outer end of said lever to swing the same on its pivot and thereby bodily displace the pad on the other end thereof.

4. In a hernia truss, a belt, a pad carried by 30 said belt for snug engagement with the affected area and provided with a finger formation, a lever pivotally mounted intermediate of its length on said pad and extending therethrough to swing 35 in a plane longitudinally of said finger formation, a pad pivotally mounted on the inner end of said lever to move bodily upwardly on the swinging of said lever, and a perineal strap operatively connected with the outer end of said 40 lever to swing same, said strap overlapping the outer side of the finger ends of said main pad and engaging same in pressure contact simultaneously with the swinging movement of said lever to cause same to exert a positive inward 45 pressure at the extremities.

THOMAS J. LE CRAS.
